[57] CLAIM

The ornamental design for a CRT adapter, substantially as shown and described.

DESCRIPTION

FIG. 1 is a front elevational view of a CRT adapter showing our new design;

FIG. 2 is a left side elevational view thereof;

FIG. 3 is a right side elevational view thereof;

FIG. 4 is a top plan view thereof;

FIG. 5 is a bottom plan view thereof;

FIG. 6 is a rear elevational view thereof.

The connector is shown broken away in FIGS. 1, 2, 3 and 6 to indicate indeterminate length and the lead wires are shaded to indicate contrast.
